UNITED STATES PATENT OFFICE.

VIRGIL H. BODLE AND WILLIAM E. JAQUITH, OF AKRON, OHIO, ASSIGNORS TO THE
B. F. GOODRICH COMPANY, OF NEW YORK, N. Y., A CORPORATION OF NEW YORK.

APPARATUS FOR ASSEMBLING SHEET MATERIAL.

Application filed March 21, 1925. Serial No. 17,445.

This invention relates to the art of assembling sheet material and has for a primary object to provide a method of and an apparatus for superimposing in accurate alignment sheets of flexible, tacky material and for pressing them smoothly and firmly together in such manner as to preclude the trapping of air between the sheets. A further object is to provide means for uniting 10 adhesively a woven fabric and thin elastic raw rubber to form a smooth, composite sheet without materially stretching either the fabric or the rubber. A further specific object of our invention is to provide means 15 for plying up a fabric lining and a raw rubber shoe section preparatory to the incorporation of the shoe section and lining, as a unit, in a shoe construction.

Of the accompanying drawings:

20 Fig. 1 is a side elevation, certain parts being broken away and others shown in section, of an apparatus embodying and adapted to carry out a preferred embodiment of our invention.

25 Fig. 2 is a section of the apparatus on line 2—2 of Fig. 1.

Fig. 3 is a plan of the apparatus of Fig. 1.

Fig. 4 is a fragmentary sectional view, similar to Fig. 2, showing the mechanism in 30 another position of operation.

Fig. 5 is a sectional detail of a supporting bracket for the presser roll.

In the drawing, 10 indicates a stationary cylinder, preferably of tubular construction, 35 axially supported by means of radially disposed spokes 12 and hub 13 on an arbor 14 and secured against rotation thereon by a key 15. The arbor projects beyond the ends of the cylinder 10 and is horizontally supported in a suitable frame which, as shown, 40 consists of two side members 16, 17, mounted on a base 19 and braced by transverse struts 20, 21 and 22, the extremities of the arbor 11 being secured to the side members 16 and 17.

45 The upper portion of the cylinder 10 constitutes a work table 24 for the assembling of sheet material. It is desirable, although not essential, to provide means for holding the work firmly on the table and any convenient 50 means for accomplishing this result may be employed. As herein illustrated, there is provided a vacuum chamber 25 having a plurality of ducts 26 leading therefrom to the rear central portion of the work table.

55 A sub-atmospheric pressure is intermittently

produced in the chamber 25 by means of an air ejector 27 which is supplied with air under pressure from a high pressure line 28 and which discharges the spent air through an exhaust pipe 29, the high pressure air 60 being supplied to and cut off from the ejector at predetermined recurring periods, as will be hereinafter more fully described.

A roll carrier of suitable construction is 65 rotatably supported in such manner as to direct a presser roll 31 and a series of material-supporting rolls 32 in rotational movements about the cylinder 10. As shown, the roll carrier consists of two annular disks 33, 34, one at each end of and concentric with 70 the cylinder 10. The disks are rigidly secured together in spaced relation by tie rods 35. At the inner sides of each of the disks 33, 34, a series of flanged wheels 36 are mounted on stub shafts 37 secured to the 75 disks 33, 34, the arrangement being such that the flanges of the wheels 36 bear lightly against the ends of the hollow cylinder 10 and the treads of the wheels bear tangentially on the cylindrical surface thereof, thus 80 definitely positioning the rotary roll carrier with relation to the cylinder 10.

The presser roll 31 is journaled in guide blocks 39 slidably mounted in guide ways 40 which are secured to the annular discs 33 85 and 34 of the roll carrier. Pins 41 secured in the blocks 39 and disposed in slots 42 of the ways 40 limit the radial movements of the guide blocks 39. Each of the guide blocks 39 extends outwardly beyond the 90 journal bearing of the roll 31 and is provided with a slot 43 in which a spur shaft 44 carrying a wheel 45 is slidably mounted. A compression spring 46 is disposed within the slot 43 so as to bear against the inner 95 end of the slot and the spur shaft 44, thus holding the spur shaft and wheel normally in an outward position against the outer end of the slot 43. The side members 16 and 17 have upwardly extending projections 100 47 upon which are secured inwardly projecting members 48 having arcuate surfaces 49 concentric with the cylinder 10 and disposed to engage the wheels 45 and move them radially inward as the presser roll 31 traverses the work table.

In handling certain materials which have a tendency to stick to the roll 31, means for preventing such adhesion may be desirable. Thus, cam clips 51 may be provided at the 110

rear of the work table to lift the roll 31, so that its first impact with the tacky material is not made at the very edge, a procedure which would tend to pick up the sheet material and break the vacuum in chamber 25, but downwardly upon the material a short distance from its edge. Further, at the trailing side of the roll 31 there may be several strand belts 54 running in grooves 55 in the roll 31 and in grooved pulleys 56 loosely mounted upon an adjacent tie rod 35. The material supporting rolls 32 are journaled in accurate journal blocks 57 which are bolted to the discs 33 and 34, as at 58, so that the rolls 32 shall be immediately in advance of the presser roll 31 and spaced from the cylinder 10.

The roll carrier is rotated about the cylinder 10 in intermittent movements, which bring the carrier to a state of rest at the two positions, indicated in Figs. 2 and 4, respectively, by suitable driving mechanism, the specific mechanism herein described being understood to be given by way of illustration. The disk 33 of the roll carrier is provided with inwardly extending lugs 60 to which are secured, as by bolts 61, a sprocket wheel 62. Supported on the base 19 of the frame is a reduction gearing 64, the low speed gear 65 of which has on its shaft a driving sprocket 66, and the high speed gear 67, a pulley 68. A belt 69 traversing the pulley 68 and a pulley 71 of an electric motor 72, suspended from the strut 20, and a sprocket chain 73 coacting with the sprockets 62 and 66, serve to transmit rotational movement from the motor through the reduction gear 64 to the roll carrier.

The pulley 71 of the electric motor 72 runs freely on the motor shaft 75, and has an internal cone-clutch-engaging surface 76 and an external brake-engaging surface 76¹. A cone-clutch 77 is slidably mounted on the end of the motor shaft 75, relative rotation thereon being inhibited by a feather in the usual manner. A servile or piston motor 78 is mounted on the frame member 16 in substantial alignment with the motor shaft 75 and comprises a cylinder 79 and a piston 80 having its piston rod 81 extending toward the clutch 77. A bell crank 82 is pivoted on an arm 83 secured to and projecting from the casing of the electric motor 72, and is apertured at its upper end to support a threaded stud 84 between and in substantial alignment with the piston rod 81 and clutch 77. The lower arm of the bell crank 82 is provided with an upstanding bracket 85 on which is mounted a brake-shoe 86, disposed to be pressed frictionally against the surface 76¹ of the pulley 71 by means of a spring 87, when the clutch mechanism is out of engagement.

The piston motor 78 is actuated by compressed air supplied from the air line 28

through a branch 88, in which is a control valve 89. The valve 89 is actuated by a starting lever 90, operated by a push rod 91, and a stop lever 92 having a tappet arm 93 positioned to be struck by tappets 94 and 95 carried on the disk 33, the tappets being located to bring the carriage to rest at the position shown in Figs. 2 and 4. As shown, the levers 90 and 92 are located remote from the valve 89 and are operatively connected therewith by an extension rod 96.

Automatic means are also provided to supply air to the ejector 27, when it is desired to hold the work to the table, and to cut off the air supply when the work is being put on and taken off from the work table. As shown, the air line 28 is provided with a valve 97, the valve stem of which has secured thereto a star wheel 98 having four projecting prongs. Tappets 99 and 100, 85 suitably disposed on the disk 34, alternately engage prongs of the star wheel 98, and thus serve alternately to open and close the valve 97 at desired points in the travel of the roll carriage.

The operation of the apparatus above described will now be briefly set forth in connection with the assembling of a fabric lining and a sheet-rubber section of a rubber shoe. It is to be understood, however, that the method and the apparatus are applicable to the assembly of sheet material of various kinds and that the specific description hereinbelow is mainly illustrative. With the valves 89 and 97 closed and the apparatus in the position shown in Figs. 1, 2 and 3, electric current is supplied to the motor 72, which runs continuously, and high pressure air is supplied to the air line 28. A shoe lining 102 is placed on the work table portion 103 24 of the cylinder 10, the rear margins of the lining covering the conduits 26. The lining 102 is normally cut from a woven fabric and is coated on one side with curable raw rubber, either by frictioning or by cementing, and hence is tacky on one side. The lining is normally placed on the work table 24, tacky side up. The operator now presses the push rod 91, opening the valve 89 which admits air through pipe 88 into the cylinder 79, thus forcing the piston 80 and its stem 81 to the right (Fig. 1), and which in turn moves the bell crank 82 in a clock-wise direction to throw the cone clutch 77 into engagement with the pulley 71 and simultaneously to release the brake-shoe 86 therefrom. The motor 72, through the intermediary of the pulley 71, belt 69, reduction gearing 64, sprockets 62 and 66, and chain 73, effects the rotation of the roll carrier. During the first movements of the roll carrier, tappet 99 on the disc 34 strikes a prong of the star wheel 98 and opens the valve 97. This admits high pressure air into the ejector 27 causing a vacuum in the chamber 25 which holds the

lining 102 securely in place as the series of material-supporting rolls 32 pass in spaced-relation thereover. Upon further rotation of the roll carrier, the tappet 94 on the disc 33 strikes the tappet arm 93 of the lever 92, cutting off the air supply from the cylinder 79, the spring 87 effecting a contra-clockwise movement (Fig. 1) of the bell crank 82 to release the clutch 77 from and to set 5 the brake-shoe 86 against the pulley 71. The adjustments are such that the roll carrier comes to rest in the position shown in Fig. 4. A raw rubber vam 104 is then laid on the rollers 32 and its rear edge is brought flush 10 with the rear edge of the lining 102 and pressed by hand at a single point onto the lining. (See Fig. 4.) Accurate alignment 15 of the two pieces is made possible by reason of the spaces between the rollers 32 which 20 permit a sufficient view of the lining for this purpose. The operator again presses the push rod 91, supplying air to the piston motor and thus setting into operation the power transmitting mechanism which rotates 25 the roll carrier. The first movements of the roll carrier bring the wheels 45 of the guide blocks 39 to bear against the arcuate surfaces 49 of the side wall extension 47, moving the spur shafts 44 of the wheels 45 away from the 30 outer ends of slots 43, and thus making effective the full force of springs 46 in pressing the roll 31 to the work. Impact of the roll 31 against the edge of the work is prevented by the cam clips 51 which raise the roll 31 35 slightly above the work and permit it to contact downwardly on the work a short distance from the edge thereof. The presser roll 31 now passes over the two sheets 102 and 104 of material and presses them together, 40 the stock 104 sliding off from the rolls 32, as the roll carrier advances. As the roll carrier approaches its original position, tappet 100 of disk 34 contacts a prong of the star wheel 98 and closes the valve 97, thus 45 cutting off the air supply to the ejector and permitting the work to be readily removed from the work table. At about the same time, the tappet 95 of the disk 33 engages the 50 arm 93 of lever 92 and closes the valve 89, and thus effects the withdrawal of the motor-clutch from its driving position, and brings the roll carrier to rest in its original position (Figs. 1, 2 and 3) ready for a succeeding operation. 55 Of particular importance is the relation of the presser roll 31 to the material supporting rolls 32. The roll 32 nearest the presser roll 31 should be close enough to prevent the two tacky sheets of material from contacting 60 prior to the line contact effected by the presser roll in passing thereover. This produces in effect a progressive rolling contact between the two sheets of material, and, where they are adhesive or adhesively coated, 65 effectually inhibits the inclusion between the

sheets of even small masses of air, which upon vulcanization would expand to cause small areas of non-adhesion or blisters in the vulcanized product.

It is to be understood that our invention is 70 not wholly limited to the described details of construction but may be variously modified within the scope of the claims.

We claim:

1. Apparatus for assembling two formed 75 sheets of material in determinate relation in adhesive, face-to-face contact, the said apparatus comprising means for supporting one of the sheets in spread condition substantially throughout its extent, means interposed 80 between the sheets for supporting the other sheet in spread condition substantially throughout its extent and in substantially its final intended position with relation to the other sheet but spaced out of contact therewith, and means for effecting such relative movement between the said sheets and the interposed support as to bring the sheets into progressive contact with each other.

2. Apparatus as defined in claim 1 in 90 which the supporting means are so constructed and arranged as to permit a portion of one sheet to be flexed into contact with the other sheet while the sheets remain positioned upon their respective supports, and including roller means for pressing together 95 the contacting portions of the sheets as they come progressively into contact with each other.

3. In a machine of the character described, 100 in combination, a table adapted to support work, a carriage adapted to move over the table, a presser roll mounted on said carriage and adapted to exert a rolling pressure directly against work supported on said table, a vacuum chamber communicating 105 with the work table surface by means of conduits to hold the work thereon, means for moving said carriage to cause the roll to traverse the table, and mechanism actuated by the movement of the carriage for creating a sub-atmospheric pressure in said vacuum chamber during a predetermined course of travel of said roll.

4. In a machine of the character described, 110 in combination, a table adapted to support work, a carriage adapted to move across said table, a presser roll mounted on said carriage and adapted to bear against said table, a material supporting means mounted on said carriage in advance of and in closely adjacent relation to said presser roll, means for moving said carriage across said table 115 including means for automatically stopping said carriage with the material supporting means over a work supporting portion of the table for aligning the material on the said material supporting means with the work on the table, and means for causing the carriage to complete its traverse of the table.

5. In a machine of the character described, in combination, a cylinder, a roll carrier rotatably disposed with respect to said cylinder and supporting a presser roll in rolling contact with said cylinder as it passes over the upper side thereof, and means secured to said carrier immediately in advance of said presser roll for supporting material in spaced relation to the cylinder, said means 10 permitting a view of the cylinder therebeneath for aligning work on the supporting means and on the cylinder.

6. In a machine of the character described, in combination, a cylinder having an upwardly exposed portion serving as a work 15 table, a carriage adapted to rotate around said cylinder, a presser roll mounted on said carriage and adapted to exert a rolling pressure on the surface of said table, a vacuum 20 chamber communicating with the work table surface by means of conduits, means for rotating said carriage about the cylinder, and mechanism activated by the rotation of said carriage for creating sub-atmospheric 25 pressure in said vacuum chamber during a predetermined arcuate travel of said roll.

7. In a machine of the character described, in combination, a cylinder having an upwardly exposed portion serving as a work 30 table, a carriage adapted to rotate around said cylinder, a presser roll mounted on said carriage and adapted to exert a rolling pressure against the surface of said table, a material supporting means mounted on said carriage in advance of and closely adjacent to 35 said presser roll, and means for rotating said carriage in intermittent movements, said means including mechanism for automatically stopping said carriage in two distinct positions, one with the work table free of 40 obstructions to permit the placing of work thereon and the other with the material supporting means over the work table to permit aligning of work on said supporting means and work on said table, and manual 45 means for starting said intermittent movements.

In witness whereof we have hereunto set our hands this 17th day of March, 1925.

VIRGIL H. BODLE.
WILLIAM E. JAQUITH.
